U.S. Cl. D23—40

FIG. 2

FIG. 1

FIG. 3

FIG. 1 is a perspective view of a T-type fitting showing my new design;

FIG. 2 is a front elevational view thereof; and

FIG. 3 is a top plan view.

The broken line representation of a faucet, a control and a gauge and the fragmentary broken line representation of a tank in FIG. 1 are for purposes of illustration only.

I claim:

The ornamental design for a T-type fitting, as shown and described.
